(57) **CLAIM**

The ornamental design for a water electrolysis device, as shown and described.

DESCRIPTION

FIG. 1 is a front view of a water electrolysis device according to the invention;

FIG. 2 is a rear view thereof;

FIG. 3 is a left side view thereof;

FIG. 4 is a right side view thereof;

FIG. 5 is a top view thereof; and,

FIG. 6 is a bottom view thereof.

All the dotted lines in the figures are directed to environment and are for illustrative purpose only. The dotted lines form no part of the claimed design.
